MUSICAL TUNING DEVICE

William D. Gladstone, New York, N. Y., assignor
to The Fred. Gretsch Manufacturing Co., Brook-
lyn, N. Y., a corporation of New York

Application July 25, 1936, Serial No. 92,478

11 Claims. (Cl. 84—411)

My invention relates to devices for tuning percussive musical instruments carrying vibratory diaphragms and especially to the tuning of drums.

The tone and resonance of a drum are dependent upon the vibrations of the two diaphragms, and as these vibrations are in turn dependent upon the degree of tautness of the diaphragms, it is evident that their relative rigidity is highly essential and that, therefore, means must be employed to control these vibrations by controlling the tautness of the diaphragms.

These essential results are obtained by varying the stretch of the drum heads.

It is to be noted that there must be a proper relative tautness between the two diaphragms and that hence, each must be stretched with relation to the other.

This is accomplished by passing the outer portion of each drum diaphragm over an end portion of the drum side and affixing it to a vertically movable flesh hoop, above which, and abutting upon it, is a vertically movable counterhoop extending above the plane of the diaphragm, the amount of stretch of the diaphragm being accomplished by a vertical movement of the counterhoop.

The evident devices for accomplishing this result are a plurality of tightening members, each having a hook or hooks placed above and upon the counterhoop with means adapted for moving the counterhoops vertically and for maintaining them in any desired position.

The usually employed devices for this purpose consist of a plurality of devices for tightening the batter head diaphragm and a plurality of independent devices for tightening the snare head diaphragm. These devices consist of a plurality of rods, threaded at one end to cooperate with a fixed threaded element attached to the drum side, the end of each rod being of angular shape to fit within a corresponding recessed key for purposes of revolution of the rod, one end of each rod carrying a hook, or hooks, to engage the upper edge of a counterhoop. The construction of these devices is such that the key ends of each series of rods are adjacent the ends of the drum carrying the diaphragm to be tightened.

In tuning a drum, the operator taps the batter head with the drum stick, notes the tone and slowly tightens, or loosens, both diaphragms during the tapping operation until the desired tone is produced. As there are usually eight, or more, tightening devices for each diaphragm, that is, sixteen or more upon the drum, and as these must be moved until a uniform stretch of the diaphragm having the proper tone is produced, it is evident that each tightening member must be revolved many times by means of a key.

As a drum cannot be conveniently reversed during the tuning operation, as the operator

must continually tap the batter head, the present employed devices require him to place his key in reversed position at the lower end of the drum in order to affect the snare head diaphragm, and as this operation must be repeated many times, the present employed method is difficult, awkward and unsatisfactory.

The device of my invention overcomes this difficulty as the operating means for both diaphragms are situated at the batter head of the drum and hence are readily and rapidly accessible.

Another great advantage of one form of the device of my invention, is means whereby the diaphragms may be controlled independently of each other and may also be controlled in unison.

When a drum is properly tuned, it will be retained in that condition for a considerable length of time under normal conditions, but because of the physical reactions of the drum head skins they are affected by changes of temperature and weather conditions, a dry hot atmosphere or a moist atmosphere, changing the tune to a more or less extent and requiring a re-tuning to obtain the proper tone.

With the present employed devices, this requires a complete new tuning by operating every one of the many tuning elements.

In one form of my device I have overcome this great disadvantage in the use of the present employed devices.

In this form of my device both diaphragms of a drum, affected as above mentioned, can be simultaneously, equally and uniformly tightened or loosened by means of a single key movement which will affect both diaphragms.

This is accomplished by a construction of elements of my device whereby a single key movement will equally tighten, or loosen, both diaphragms.

It will thus be noted that when a drum carrying my device is properly tuned, and the tone subsequently changed by weather conditions, the original tone can be recovered by the simultaneous tightening, or loosening, of both diaphragms.

The above mentioned, and other, advantages incident to the employment of the devices of my invention will be evident upon a consideration of this specification and its accompanying drawings, in which similar parts are indicated by similar characters.

Figure 1 is a front view of one of the tuning devices of my invention shown attached to a drum.

Figure 2 is a section through the line 2—2 of Figure 1.

Figure 3 is a vertical section through a key adapted to operate with the devices of Figures 1 and 2.

Figure 4 is a front view of a modified form of

the device of my invention, shown attached to a drum.

Figure 5 is a section through the line 5—5 of Figure 4.

5 The particular form of a device of my invention shown in Figures 1 and 2 consists of a tubular supporting member 10, having the two extended lugs, or legs, 11, 11 which are fixedly attached to the side A of a drum, by means of the 10 screws 12, 12. The interior face of the upper portion of the supporting member 10 is threaded and the bore of the member 10 is reduced in size at the lower portion 13.

15 Threaded within the supporting member 10 is an externally threaded tubular member 14, the upper portion of which terminates in an angular key receiving member 15. The tubular member 14 passes through the bore of a tightening member consisting of the body portion 16, the arms 20 17, 17 and the two hooked members 18, 18 which are shown as extending inwardly over the counterhoop B at the batter head end of the drum. The batter head diaphragm C of the drum passes over the inwardly bent portion D of the side A, thence downwardly and around the flesh hoop E and the counterhoop B abutting upon the flesh hoop E and being vertically movable along the 25 side A of the drum.

30 It will thus be seen that if the angular recess 19 of the key shown in Figure 3 be placed over the element 15 of the tubular member 14 and be revolved in one direction the tubular member 14 will move downwardly, the hooks 18, 18 will move the counterhoop B and the flesh hook E downwardly thus tightening the batter head diaphragm C, and that a reverse movement of the 35 key will loosen the batter head diaphragm C.

35 Positioned within the tubular tightening member 14 and vertically movable therein is a member 20, the upper end 21 of which is angular to receive a key. The member 20 carries a fixed guiding collar 22 and a fixed collar 23 capable of abutting upon the shoulder 24 formed in the tubular member 14 by its reduced bore. The 40 lower end 25 of the member 20 is threaded and is capable of being threaded within the threaded bore 26 of the snare tightening member which consists of the body 27, the two extended arms 28, 28 and the two hook members 29, 29 which are shown as extended inwardly over the counterhoop B' at the snare end of the drum. The snare head diaphragm C' of the drum passes over the inwardly bent portion D' of the side A, thence upwardly and around the flesh hoop E' and the 45 counterhoop B' abutting upon the hoop E' and being vertically movable along the side A of the drum.

50 It will thus be seen that if the angular recess 30 of the key shown in Figure 3 be placed over the element 21 of the member 20 and be revolved in one direction the member 20 will move upwardly, the hooks 29, 29 will move the counterhoop B' and the flesh hoop E' upwardly, thus tightening the snare head diaphragm C' and that a reverse movement of the key will loosen the snare head diaphragm C'.

55 The key shown in Figure 3 has three operating recesses, recess 19 being formed to fit the member 15 for tightening the batter head diaphragm, the recess 30 for tightening the snare head diaphragm, and the recess 31 in the central stem arm is so formed that the outer enlarged portion will fit the element 15 and the inner reduced portion will fit the element 21 and hence it is 60 evident that when this master portion 31 of the

key is employed it will revolve both the tubular member 14 and the member 20 thus simultaneously tightening, or loosening, both the batter head diaphragm and the snare head diaphragm, it being noted that the threads in the members 5 10 and 27 match each other, in that both are shown as right-hand threads.

65 It is obvious that the short hollow headed and apertured downwardly extended stem portion shown in Figure 3 provides for the attachment of 15 a key chain, if so desired.

70 The simplicity and ease of its removal from and attachment to a drum are evident when it is considered that the device can be disassembled by simply revolving the member 20 from its threaded attachment with the body member 27 and withdrawing it from the member 14 and then revolving the member 14 from its threaded attachment with the supporting member 10 and withdrawing it from the body member 16. It will 20 thus be seen that the device consists of only the three members 10, 14 and 20 and the two hooked members 16 and 27.

75 The usual method for operating the device consists in alternately tightening the diaphragms 25 C and C' by the employment of the ends 19 and 30 of the key until the desired resonance or tone is obtained. This condition is maintained until, because of atmospheric conditions, or otherwise, the diaphragms have become unduly 30 loosened or tightened in which event both diaphragms are simultaneously and uniformly tightened or loosened, by the employment of the key end 31 as above described, thereby to produce the original desired resonance or tone, all of 35 which operations are performed at the batter head portion of the drum, thus avoiding the necessity of reversing the drum.

80 The device shown in Figures 4 and 5 is designed to allow of the tightening, or loosening, 40 of both diaphragms of a drum, without the necessity of reversing the drum during the process and to allow of the accomplishment of this desirable result with a minimum of mechanical parts.

85 This particular form of a device of my invention consists of a bracket 40, having the two extended lugs 41, 41 which are fixedly attached to the side A of a drum by means of the screws 42, 42.

90 That portion of the device adapted for tightening, or loosening, the batter head diaphragm C consists of a rod 43, the upper end 44 of which is of angular formation, the rod carrying the fixed collar 45, the lower end 46 of the rod 55 43 being threaded to thread with the threaded bore 47 of the support 40. The rod 43 passes also through the opening 48 of the batter head tightening means which consists of the body 49, the arms 50, 50 and the hooked members 51, 51 60 shown as extended over the batter head counterhoop B.

95 It is evident that a revolution of the rod 43 will tighten, or loosen, the batter head diaphragm C, dependent upon the direction of 65 revolution.

100 The elements of construction adapted for tightening, or loosening, the snare head diaphragm C' consist of a rod 52, the upper end 53 of which is of angular formation, the rod 52 70 carrying the fixed collar 54 and having a threaded lower end 55. The rod 52 passes through the opening 56 in the body member 49, the openings 57 and 58 in the supporting member 40, and is threaded within the threaded bore 59 of the 75

snare tightening member which consists of the body 60, the arms 61, 61 and the hooked members 62, 62 which are shown as extending over the snare counterhoop B'. It is evident that a revolution of the rod 52 will tighten, or loosen, the snare head diaphragm C', dependent upon the direction of revolution.

The ends 44 and 53 may be of the same size and formation, thus allowing the use of the same key for acting upon both diaphragms, if desired.

It will thus be seen that either, or both, diaphragms can be tightened or loosened without reversing the drum.

The devices of my invention, therefore, present many advantages over the devices now employed for the purposes described and allow of a more accurate and more easy accomplishment of the proper tuning of a drum.

I do not limit myself to the particular size, shape, number or arrangement of parts as shown and described, as these are given solely for the purpose of clearly describing my invention.

What I claim is:

1. In a drum tuning device, in combination, a supporting member fixedly attachable to the side of a drum, a tightening member detachably engageable with a counterhoop of a drum, a rotatable adjusting tie rod having a shoulder in abutment with one of said members and having threaded adjusting engagement with the other one of said members, another tightening member detachably engageable with the other counterhoop of a drum, a rotatable adjusting tie rod extending between said latter tightening member and said supporting member and having a shoulder in abutment with one of these members and having threaded adjusting engagement with the other one of these members, one of said rods having an end portion positioned to be accessible from the outer end of one of said tightening members and by means of which this adjusting rod can be individually rotated, and an end extension upon the other said rod having an end portion positioned to be accessible from the outer end of the same said tightening member from which said rod end portion is accessible and by means of which this said other adjusting rod can be individually rotated.

2. In a drum tuning device, in combination, a supporting member fixedly attachable to the side of a drum, a tightening member detachably engageable with a counterhoop of a drum, a rotatable adjusting tie rod having a shoulder in abutment with said tightening member and having threaded adjusting engagement with said supporting member, an end portion of said rod being accessible from the outer end of said tightening member and by means of which said adjusting rod can be individually rotated, another tightening member detachably engageable with the other counterhoop of a drum, a rotatable adjusting tie rod having a shoulder in abutment with said supporting member and having threaded adjusting engagement with said latter tightening member, and an end extension upon said latter rod extending from said supporting member to said first mentioned tightening member and from the outer end of which tubular rod an end portion of said extension is accessible and by means of which said latter adjusting rod can be individually rotated.

3. In a drum tuning device, in combination, a supporting member fixedly attachable to the side of a drum, a tightening member detachably engageable with a counterhoop of a drum, a ro-

tatable adjusting tie rod having a shoulder in abutment with said tightening member and having threaded adjusting engagement with said supporting member, an end portion of said rod being accessible from the outer end of said tightening member and by means of which said adjusting rod can be individually rotated, another tightening member detachably engageable with the other counterhoop of a drum, a rotatable adjusting tie rod having a shoulder in abutment with said supporting member and having threaded adjusting engagement with said latter tightening member, an end extension upon said latter rod extending from said supporting member to said first mentioned tightening member and from the outer end of said first mentioned tightening member an end portion of said extension is accessible and by means of which said latter adjusting rod can be individually rotated, and coupling means disconnectably engageable concomitantly with said rod end portion and with said rod extension end portion and being thus adapted for simultaneously rotating both of said adjusting rods together as a unit.

4. In a drum tuning device, in combination, a supporting member fixedly attachable to the side of the drum, a tightening member detachably engageable with a counterhoop of a drum, a rotatable tubular adjusting rod tying said members together and having threaded adjusting engagement with at least one of said members, an outer end portion of said tubular rod being accessible from the outer end of said tightening member and by means of which said tubular adjusting rod can be individually rotated, another tightening member detachably engageable with the other counterhoop of a drum, a rotatable adjusting rod tying together said latter member and said supporting member and having threaded adjusting engagement with at least one of these members, and an end extension upon said latter rod extending into said tubular rod and from the outer end of which tubular rod an end portion of said extension is accessible and by means of which said latter adjusting rod can be individually rotated.

5. In a drum tuning device, in combination, a supporting member fixedly attachable to the side of a drum, a tightening member detachably engageable with a counterhoop of a drum, a rotatable tubular adjusting rod tying said members together and having threaded adjusting engagement with at least one of said members, an outer end portion of said tubular rod being accessible from the outer end of said tightening member and by means of which said tubular adjusting rod can be individually rotated, another tightening member detachably engageable with the other counterhoop of a drum, a rotatable adjusting rod tying together said latter member and said supporting member and having threaded adjusting engagement with at least one of these members, an end extension upon said latter rod extending into said tubular rod and from the outer end of which tubular rod an end portion of said extension is accessible and by means of which said latter adjusting rod can be individually rotated, and coupling means disconnectably engageable concomitantly with the outer end portion of said tubular rod and with the end portion of said rod extension and being thus adapted for simultaneously rotating both of said adjusting rods together as a unit.

6. In a drum tuning device, in combination, a supporting member fixedly attachable to the side

- of a drum, a tightening member detachably engageable with a counterhoop of a drum, a rotatable tubular adjusting tie rod having a shoulder in abutment with one of said members and having threaded adjusting engagement with the other one of said members, an end portion of said tubular rod being accessible from the outer end of said tightening member and by means of which said tubular adjusting rod can be individually rotated, another tightening member detachably engageable with the other counterhoop of a drum, a rotatable adjusting tie rod extending between said latter tightening member and said supporting member and having a shoulder in abutment with one of these members and having threaded adjusting engagement with the other one of these members, and an end extension upon said latter rod extending into said tubular rod and from the outer end of which tubular rod an end portion of said extension is accessible and by means of which said latter adjusting rod can be individually rotated.
7. In a drum tuning device, in combination, a supporting member fixedly attachable to the side of a drum, a tightening member detachably engageable with a counterhoop of a drum, a rotatable tubular adjusting tie rod having a shoulder in abutment with one of said members and having threaded adjusting engagement with the other one of said members, an end portion of said tubular rod being accessible from the outer end of said tightening member and by means of which said tubular adjusting rod can be individually rotated, another tightening member detachably engageable with the other counterhoop of a drum, a rotatable adjusting tie rod extending between said latter tightening member and said supporting member and having a shoulder in abutment with one of these members and having threaded adjusting engagement with the other one of these members, an end extension upon said latter rod extending into said tubular rod and from the outer end of which tubular rod an end portion of said extension is accessible and by means of which said latter adjusting rod can be individually rotated, and coupling means disconnectably engageable concomitantly with the outer end portion of said tubular rod and with the end portion of said rod extension and being thus adapted for simultaneously rotating both of said adjusting rods together as a unit.
8. In a drum tuning device, in combination, a supporting member fixedly attachable to the side of a drum, a tightening member detachably engageable with a counterhoop of a drum, a rotatable tubular adjusting tie rod having a shoulder in abutment with said tightening member and having threaded adjusting engagement with said supporting member, an end portion of said first mentioned tightening member beyond its said shoulder being accessible from the outer end of said tightening member and by means of which said tubular adjusting rod can be individually rotated, another tightening member detachably engageable with the other counterhoop of a drum, a rotatable adjusting tie rod having a shoulder in abutment with said supporting member and having threaded adjusting engagement with said latter tightening member, and an end extension upon said latter rod extending into

said tubular rod and from the outer end of which tubular rod an end portion of said extension is accessible and by means of which said latter adjusting rod can be individually rotated.

9. In a drum tuning device, in combination, a supporting member fixedly attachable to the side of a drum, a tightening member detachably engageable with a counterhoop of a drum, a rotatable tubular adjusting tie rod having a shoulder in abutment with said tightening member and having threaded adjusting engagement with said supporting member, an end portion of said tubular rod beyond its said shoulder being accessible from the outer end of said tightening member and by means of which said tubular adjusting rod can be individually rotated, another tightening member detachably engageable with the other counterhoop of a drum, a rotatable adjusting tie rod having a shoulder in abutment with said supporting member and having threaded adjusting engagement with said latter tightening member, an end extension upon said latter rod extending into said tubular rod and from the outer end of which tubular rod an end portion of said extension is accessible and by means of which said latter adjusting rod can be individually rotated, and coupling means disconnectably engageable concomitantly with the outer end portion of said tubular rod and with the end portion of said rod extension and being thus adapted for simultaneously rotating both of said adjusting rods together as a unit.

10. In a drum tuning device, in combination, an interiorly threaded supporting member fixedly attached to the side of a drum, adjustable drum-head tightening means adapted for detachably tying together said supporting member and a batter hoop of a drum and including a rotatable threaded adjusting member threaded within said supporting means, other interiorly threaded tightening drumhead tightening means for the bottom counterhoop of said drum, and second adjustable drum-head tightening means adapted for detachably tying together the batter head tightening means and the bottom head tightening means including a rotatable threaded member threaded within said bottom drum-head tightening member, said two tying members carrying means whereby they can be separately rotated.

11. In a drum tuning device, in combination, an interiorly threaded supporting member fixedly attached to the side of a drum, adjustable drum-head tightening means adapted for detachably tying together said supporting member and a batter hoop of a drum and including a rotatable threaded adjusting member threaded within said supporting means, other interiorly threaded tightening drum-head tightening means for the bottom counterhoop of said drum, and second adjustable drum-head tightening means adapted for detachably tying together the batter head tightening means and the bottom head tightening means including a rotatable threaded member threaded within said bottom drum-head tightening member, said two tying members being adjacent to each other, and adjacent to the same counterhoop and carrying means whereby they can be separately rotated.

WILLIAM D. GLADSTONE.
